UNITED STATES PATENT OFFICE.

EUGENE W. SCHELLENTRAGER, OF CLEVELAND, OHIO, ASSIGNOR TO THE ATLAS CAR & MANUFACTURING COMPANY, OF CLEVELAND, OHIO, A CORPORATION OF OHIO.

DUMP CAR.

Application filed March 7, 1927. Serial No. 173,555.

This invention relates to gate operating mechanism for dump cars, wherein a horizontal shaft extending through the sides of the car hopper is employed as part of the 5 gate operating mechanism.

In such arrangements it has been heretofore customary to perforate the necessary hopper sides to accommodate the shaft, this 10 practice requiring longitudinal insertion and withdrawal of the shaft and hence in many cases practically complete dismantling of the car where the desired object is only removal of the shaft.

According to my invention, briefly, instead 15 of merely perforating the hopper side I cut away a portion thereof downwards from the upper extremity, forming a vertically extending slot into which the shaft may be lowered; thereafter I insert a casting which 20 serves as a part of the shaft bearing and also to complete the cut away portion of the hopper and reinforce the same.

The exact nature of my invention will be 25 apparent from the description taken in connection with the accompanying drawings which illustrate by way of example portions of a commercial type of dump car, and in which Fig. 1 is a partial side elevation of the car showing features pertinent to my invention; Fig. 2 is a similar end elevation of the 30 same showing details of the gate operating mechanism; and Figs. 3 and 4 are end and sectional views respectively of the essential parts of my invention.

Referring now specifically to the drawings, 35 1 is the frame of the car supported in the usual manner by trucks 2 of any standard type, and in turn supporting a hopper 3 of sloping ends 4.

The hopper is provided around its upper 40 edge with a heavy rail member 5, and in its bottom with a pair of gates 6 whereby the contents of the hopper may be retained or dumped as desired. The gates are arranged 45 to be operated by a shaft 7 extending longitudinally of the car through the hopper and hence through the sides thereof, and supported suitably as in bearings 8 outboard of the hopper. In the illustration chosen the 50 shaft 7 is in connection with the gates 6 through linkage comprising the tension members 9 and 10 and levers 11 whereby a partial rotation of shaft will serve to open or close the gates, the shaft being actuated 55 by a fluid motor 12 of reciprocable type,

through an enclosed rack and pinion arrangement, details of which are not specifically shown.

Were the end 4 solid and merely perforated to receive the shaft it is obvious that 60 only endwise removal of the same would be possible. According to my invention however, I cut away a portion of the end downwards from the top sufficiently to receive a lower bearing member 13 adapted to support the shaft. I provide also an upper bearing member 14 adapted to cooperate with the member 13 to completely encircle the shaft and to co-operate with both the members 13 and the end 4 of the hopper to 65 complete the latter by covering the cut away portion. The upper extremity of the casting 14 is formed with substantial flange 15 which serves to greatly strengthen the hopper, as does in fact the whole arrangement. A 70 diagonally flanged gland member 16 may also be provided as indicated secured with both members 13 and 14 to reinforce the 75 assembly thereof.

The result of my arrangement is that removal of shaft 7 requires merely removal of the member 14, whereupon the shaft may be raised directly upwards and out of the car.

Such an arrangement allows preassembly 80 of levers 11 upon the shaft which would otherwise be impossible, and positioning of the members 11 close in under the overhanging portion of the side 4.

What I claim is:

1. In a car of the type described, a hopper, a gate at the bottom thereof, a gate operating mechanism including a shaft extending horizontally into said hopper through a side thereof, and means for positioning said shaft 90 in said side, said means comprising a lower bearing member supported in a portion of said side cut away to receive the same, and a bearing and closure member cooperating with said lower bearing member to form a 95 journal for said shaft, co-operating with said cut away portion to complete and reinforce said side, and removable to allow removal of said shaft vertically.

2. In a car of the type described, a hopper, 100 a gate at the bottom thereof, a gate operating mechanism including a shaft extending horizontally into said hopper through a side thereof, and means for positioning said shaft in said side, said means comprising a lower 110

bearing member supported in a portion of said side cut away to receive the same, a part of said side portion cut away including a substantial top rail, and a bearing and closure member cooperating with said lower bearing member to form a journal for said shaft, cooperating with said cut away portion to complete and reinforce said side, and removable to allow removal of said shaft vertically.

3. In a car of the type described, a hopper, a gate at the bottom thereof, gate operating mechanism including a shaft extending horizontally into said hopper through a side thereof, and means for positioning said shaft in said side, said means comprising a lower bearing member, supported in a portion of said side cut away to receive the same, a bearing and closure member cooperating with said lower bearing member to form a journal for said shaft, cooperating with said cut away portion to complete and reinforce said side, and removable to allow removal

of said shaft vertically, and a gland surrounding said shaft and secured with both 25 said bearing members.

4. In a car of the type described, a sloping sided hopper, a gate at the bottom thereof, gate operating mechanism including a shaft extending horizontally into said hopper through a sloping side thereof and members mounted upon said shaft outside said hopper and beneath the upper portion of said side, and means for positioning said shaft in said side, said means comprising, a lower bearing 35 member supported in a portion of said side cut away to receive the same, and a bearing and closure member cooperating with said lower bearing member to form a journal for said shaft, cooperating with said cut away 40 portion to complete and reinforce said side, and removable to allow removal of said shaft vertically.

In testimony whereof I hereby affix my signature.

EUGENE W. SCHELLENTRAGER.
